UNITED STATES PATENT OFFICE.

JOHANN WIECHMANN, OF DETROIT, MICHIGAN.

LUBRICATING MEANS FOR METERING DEVICES.

1,278,268.

Specification of Letters Patent. Patented Sept. 10, 1918.

Application filed January 22, 1917. Serial No. 143,849.

To all whom it may concern:

Be it known that I, JOHANN WIECHMANN, a subject of the Emperor of Germany, residing at Detroit, in the county of Wayne 5 and State of Michigan, have invented certain new and useful Improvements in Lubricating Means for Metering Devices, of which the following is a specification, reference being had therein to the accompanying drawings.

In gas meters and like devices wherein a collapsible wall of leather or the like is always under expansion or contraction, the fabric is liable to become dry or brittle and 15 to crack, thereby requiring frequent renewal. Various devices for lubricating this flexible wall in apparatus of this kind have been used but the unequal distribution of the lubricant or the contact thereof with the 20 gas or liquid passing through the bellows, militates against successful lubrication. Furthermore renewal of the lubricant in devices of this character requires the taking down and reassembling of the meter or like 25 instrument as a whole.

This invention relates to means for lubricating the diaphragms of gas meters or like devices and to an arrangement thereof that insures a constant supply equally to all 30 parts of the diaphragm fabric.

Another feature of the invention is an arrangement which prevents contact between the body of the lubricant and the gas. A further advantage is the fact that the lubricant 35 may be renewed without any dismantling of the device.

The invention consists in the matters hereinafter set forth, and more particularly pointed out in the appended claims.

40 In the drawings.

Figure 1 is a view in section through a meter provided with a lubricating device that embodies features of the invention;

Fig. 2 is a view in front elevation of the 45 bellows bag and lubricating annulus shown in Fig. 1;

Fig. 3 is a slight modification of the device;

Fig. 4 is a view in detail showing an arrangement for a double diaphragm; and

Fig. 5 is a view in detail showing a reserve reservoir in connection with the device.

Referring to the drawings a usual external casing 1 of a type and construction de-

pendent upon the style of meter used, contains the usual diaphragm 2 which in part at least, has a bellows bag of flexible material, the mouth of which is drawn over a rim 3 of the casing. A hollow annulus 4 encircles the mouth of the bag, its separated end portions being connected by a binding bolt 6 which holds the bag firmly in position. There is a channel 7 through the wall of the annulus 4 which contacts with the 60 bag mouth, or a continuous slot 8 or a series of perforations if preferred. A filler pipe 9 extending without the casing is used to introduce lubricant into the annulus.

As indicated in Fig. 3, the bellows bag 10 70 may be clamped between opposing sections 11 and 12 of the casing, in which instance an oil chamber 13, one wall of which is the bag neck, is formed in one of the sections and is provided with a filler pipe 14 whereby a supply of lubricant may be introduced and maintained around the entire mouth of the bag. If the meter is provided with a double bellows or bag, the mouths 15 of which are secured around the casing frame 75 16 as indicated in Fig. 4, the lubricant container may be formed by the obliquely disposed annular walls 17 and 18, with outlet apertures 19 permitting contact of the lubricant with the bag and a filler opening 20 80 85 common to the inner annular chambers that are thus formed.

If the meter is in a place hard of access, and under certain other conditions of service that militate against regular inspection, 90 it is desirable to have an auxiliary lubricant container 21, as shown in Fig. 5, that provides an excess of lubricant discharging through the filler pipe 22 into the annular space 23 which thereby keeps a constant supply 95 for the bellows wall 24.

Because of this construction and arrangement, lubricant is evenly distributed by capillary action and seepage uniformly around the bellows bag opening or mouth 100 100 so that the body of the wall is kept evenly pliable. Furthermore the lubricant body does not come in contact with the gases or other fluid passing through a meter and consequently does not become vitiated.

Furthermore the disadvantage of the common form of lubrication wherein the lubricant is held in a reservoir in the lower part of the casing into which the bag dips, is avoided, first, because the lubricant is out 110

of contact with the gas, and second, because the upper portion of the bag is as thoroughly oiled as the other portions.

Obviously, changes in the details of construction may be made without departing from the spirit of my invention and I do not care to limit myself to any particular form or arrangement of parts.

What I claim is:—

1. In a metering device having a flexible bellows wall secured along a circumferential marginal portion thereof, means for impregnating the fabric of the wall constantly and uniformly with a lubricant, by maintaining a supply in constant contact with said marginal portion thereof throughout its entire extent.

2. In a metering device, a diaphragm of flexible fabric secured along a circumferential margin thereof, and an annular lubricant retainer adapted to maintain a supply of lubricant in constant contact with the attached portion throughout the entire circumference thereof.

Copies of this patent may be obtained for five cents each, by addressing the "Commissioner of Patents, Washington, D. C."

3. In a metering device a flexible diaphragm, a container adapted to maintain a supply of lubricant within the device and out of contact with any fluid passing through the meter, and to maintain the margin of the diaphragm in constant contact throughout its entire circumferential extent with the contents of the container.

4. In a gas metering device, a flexible diaphragm of substantially circular contour, the peripheral margin of which is fixed in the meter, and an annular lubricant containing chamber, one wall of which is faced by the retained marginal portion whereby the contents of the container is uniformly distributed and disseminated to impregnate uniformly the entire fabric of the diaphragm.

In testimony whereof I affix my signature in the presence of two witnesses.

JOHANN WIECHMANN.
